UNITED STATES PATENT OFFICE.

WILLIAM J. BAILEY, OF CLEVELAND, OHIO.

DESIGN FOR A HELP-SELF COUNTER AND DISPLAY-CABINET.

56,263.

Specification for Design.

Patented Sept. 14, 1920.

Application filed August 7, 1919. Serial No. 315,995. Term of patent 14 years.

To all whom it may concern:

Be it known that I, WILLIAM J. BAILEY, a citizen of the United States, residing at Cleveland, in the county of Cuyahoga and State of Ohio, have invented a new, original, and ornamental Design for a Help-Self Counter and Display-Cabinet, of which the following is a specification, reference being had to the accompanying drawings, forming a part thereof.

In said drawing, Figure 1 is a perspective view; Fig. 2 is a sectional elevation; Fig. 3 is another sectional elevation of a help self counter and display cabinet showing my new design.

I claim:

The ornamental design for a help self counter and display cabinet substantially as herein shown.

WILLIAM J. BAILEY.
